Primary Examiner — Catheri Oliver-Garcia*Assistant Examiner* — Rebekah Caruso(74) *Attorney, Agent, or Firm* — Fitzpatrick, Cella, Harper & Scinto(57) **CLAIM**

The ornamental design for a shingle, as shown and described.

DESCRIPTION

FIG. 1 is a top plan view of a first embodiment of a shingle; FIG. 2 is a front elevation thereof; FIG. 3 is a rear elevation thereof; FIG. 4 is a right side view thereof; FIG. 5 is a perspective view thereof; FIG. 6 is a bottom plan view thereof; FIG. 7 is a top plan view of a second embodiment of a shingle; and, FIG. 8 is a top plan view of a third embodiment of a shingle. The broken lines shown in the drawings are for illustrative purposes only and depict portions of the shingle that form no part of the claimed design.

1 Claim, 3 Drawing Sheets# US D765,886 S
